COLLAPSIBLE CHAIR

Amos G. Parry, Granville, N. Y., assignor to The
Telescope Folding Furniture Company, Inc.,
Granville, N. Y., a corporation of New York

Application October 27, 1937, Serial No. 171,187

1 Claim. (Cl. 155—117)

This invention relates to collapsible chairs and has for an object the provision in such a chair of means for easily and quickly adjusting the back portion from a sitting position to a prone position and intermediate positions.

In a chair embodying the invention, the front and rear legs have terminal pivotal connections at their upper ends and the back and seat portions are pivotally connected by means which 10 pivotally support the back from the rear legs. Adjustable connections are provided between the front ends of the arms and one set of legs near their juncture with the other set of legs. These 15 connections are of such a type that they may be adjusted merely by lifting the front ends of the arms to arrange the back portion in any one of several positions between sitting position and prone reclining position.

Other objects, novel features and advantages 20 of this invention will become apparent from the following specification and accompanying drawing, wherein:

Fig. 1 is a side elevation of a chair embodying the invention;

Fig. 2 is a fragmentary enlarged section substantially on the line 2—2 of Fig. 3;

Fig. 3 is a section on the line 3—3 of Fig. 2, and

Fig. 4 is a section on the line 4—4 of Fig. 1.

The chair is provided with a set of front legs 10 and a set of rear legs 11, which are joined together near their upper extremities by pivot pins 12. A seat portion 13 is attached to the front legs 10 by pivot pins 14 and is attached to a back portion 15 by pins 16 having extensions which rest upon the rear legs 11. Links 17 are pivotally connected at one end to the pins 16 and at the other end are pivoted to rear legs 11 by rivets 18. A strip 19 of canvas or other suitable material is attached at one end to the front end of the seat portion 13 and at the other end to the upper end of the back portion 15 and serves as the actual support for the person using the chair.

At the front ends of the rear legs 11 are attached brackets 20 each having an upstanding portion provided with an opening 21. Arms 22 are connected at their rear ends to the back portion by pivot pins 23 and have at their front ends guide members 24 having offset ends attached to the under surface of the arms. Each guide member 24 extends through the opening 21 in a bracket 20. A plate 25 engages the bottom face of each arm 22 and is held in place by the same screws which attach the guide member 24 to the arm. Each plate 25 has a downwardly extending flange provided with a plurality of inclined slots or notches 26 in which the top of the bracket 20 is selectively receivable. The plate 25 is also provided with a second down-

wardly extending flange 25a which overlies the notches and the upper end of the bracket 20 to prevent injury to a person by insertion of the fingers between the guide member and the flange 25a.

The normal sitting position of the chair is shown in full lines in Fig. 1, while the adjusted position is shown in dotted lines. The back 15 is moved from the position shown in full lines to the position shown in dotted lines merely by 10 lifting the front ends of the arms 22 to disengage the rearmost notches 26 from the brackets 20 (see Fig. 2) and move the arms rearwardly and then downwardly to engage the next notch 26 over the bracket 20. If it is desired to move 15 the back into full reclining or prone position, the same operation is repeated, but with the foremost notches 26 eventually received over the brackets 20. Adjustment of the back may be effected by a person occupying the chair without 20 getting up therefrom as it is necessary only to lift the front ends of the arms and then move them backwardly or forwardly according to the adjustment desired. The inclination of the notches 26 prevents accidental disengagement 25 thereof from the brackets thereby preventing accidental movement of the back from its erect to its prone position and facilitates movement of the back from its rearmost to its foremost position.

I claim:

A collapsible chair comprising front and rear legs having terminal pivotal connections at their upper extremities, seat and back portions having pivotal connection with each other and with 35 the rear legs, pivotal connections between the front ends of said seat portions and said front legs, arms connected at their rear ends to the back portions, a one-piece apertured bracket attached to each rear leg adjacent its pivotal connection with the front leg, a sheet metal guide member supported by each arm and having an offset portion passing through the bracket aperture, and a sheet metal plate attached to each arm and having a portion bent downwardly to 45 form a flange, said flange having cut-out portions in its bottom edge providing a plurality of slots in which said bracket is selectively receivable whereby the position of the back portions may be adjusted by lifting the front ends of the 50 arms and moving said arms forwardly or rearwardly, said slots having downwardly inclined portions extending rearwardly to facilitate forward movement of the arms and prevent accidental rearward movement thereof and each 55 plate having a second portion bent downwardly to form a flange overlying a portion of the guide member and the upper end of said bracket.

AMOS G. PARRY. 60
